UNITED STATES PATENT OFFICE

JOSEPH A. WADDELL, OF WILLIAMSPORT, PENNSYLVANIA, ASSIGNOR TO SPENCER HEATER COMPANY, OF WILLIAMSPORT, PENNSYLVANIA, A CORPORATION OF PENNSYLVANIA

ROTARY ASH RECEIVER

Application filed May 8, 1929. Serial No. 361,456.

This invention relates to rotary ash receivers for furnaces and the like and has for its object to provide a construction more efficient in operation and less costly to manufacture than those heretofore proposed.

With these and other objects in view the invention consists in the novel details of construction and combinations of parts as will be more fully hereinafter disclosed and particularly pointed out in the claims.

Referring to the accompanying drawings forming a part of this specification in which like numerals designate like parts in all the views—

Fig. 1 is a central vertical sectional view of a device made in accordance with this invention;

Fig. 2 is a top plan view of the parts shown in Fig. 1 with the cover plates removed;

Fig. 3 is a front elevational view of a portion of the device illustrating the disposition of an ash can thereon;

Fig. 4 is a detail view partly in section still further illustrating the disposition of an ash can on the device, taken as on the line 4—4 of Fig. 3 and looking in the direction of the arrows;

Fig. 5 is a top plan view of the device with the cover plates in position;

Fig. 6 is a horizontal sectional view of a portion of the cover of the device, taken as on the line 6—6 of Fig. 5 and looking in the direction of the arrows;

Fig. 7 is an enlarged detail view illustrating a corner formation of the cap plate 40 to accommodate the overlapping edges of two adjoining cover sections;

Fig. 8 is an enlarged top plan view of the central portion of the device illustrating the means by which the ash cans may be moved from one position to another;

Fig. 9 is a vertical sectional view of the parts shown in Fig. 8 taken as on the line 9—9 thereof and looking in the direction of the arrows; and

Fig. 10 is a perspective detail illustrating how the handle is applied to the upper supporting plate of the device in order to rotate the same.

One of the objects of this invention is to

provide a construction which is disposed below the level of the floor of the furnace room so that it is out of the way. Another object is to provide a device which has a plural number of ash receiving receptacles which can be periodically moved beneath the ash pit of the furnace while, at the same time, making possible the ready removal of any desired ash can. A still further object of the invention is to provide a rotary ash receiving device which is freely supported and rotated upon its bearings regardless of any weight that may be placed on the covers to the device. Other objects will become apparent from the following description of the embodiment of the invention shown in the drawings.

The floor surface of the furnace room is indicated at 1 below which there is built a pit 2 which may be lined as indicated at 3 with metal or the like or which may be left in the natural surface finish of the concrete or other material of which the pit is formed. The pit is preferably circular and in the center of the floor 4 thereof there is rigidly secured, as by the bolts 5, a foot plate 6 centrally recessed on its upper face to serve as a socket for a vertical post 7 preferably formed as shown in Fig. 1. That is to say said post comprises a heavy round main section with reduced end portions the lowermost 8 of which seats in the recess of the foot plate 6 and the upper 9 of which is adapted to support the covers of the pit.

A circular plate 10 is fitted around the lower post spindle 8 with a roller or other suitable thrust bearings 11 interposed between said plate and the shoulder of said spindle. The plate 10 has a central upwardly extending collar, internally threaded, to receive the lower end of a cylindrical casing 13 encompassing the major portion of the post 7 in spaced relation thereto so that grease or other lubricant may be placed within the intervening space to make the rotary movement of the device easier. A similar roller thrust bearing 15 is disposed on the upper spindle 9 between the shoulder of the post and a cap plate 16 which likewise has a central collar

17 internally threaded to engage the upper end of the casing 13.

The base of turntable of the device comprises the lower plate 10 to which is rigidly secured the inner ends of radially extending angle iron members 18 the outer ends of which are rigidly interconnected by angle iron members 19 and gusset plates 20, see Fig. 2. Also there are provided intermediate angle iron members 21 the ends of which are rigidly secured by gussets 22 to intermediate points of the radial angles 18. The angle members are all so assembled that there is formed a perfectly plane seat of triangular shape to receive the bottom of an ash can 25. In order that the turntable with its ash cans may be more stable there are provided stay rods 26 connecting the outer extremities of the angles 18 with the upper plate 16 all in a manner as will be readily understood from the drawings.

There thus results a skeleton construction of star shape providing a plurality of triangularly shaped spaces each for the reception of an ash can, the drawings having six such spaces. In thus making the device hexagonal in form the angles 18 and 19 can be precut all of the same length and drilled at the same points to receive the rivets or bolts 30 by which they are secured in place. The stay rods 26 extend obliquely upwardly and inwardly to the top plate 16 where the upper ends of said rods pass through openings in said plate into inclined recesses 27 in order that the threaded ends may receive nuts by which the rods are tightened. It is to be observed from Fig. 1 that said recesses are so cast in the plate 16 that the upper ends of said rods together with their nuts will lie completely below the upper surface of said plate. In between each pair of recesses 27 there is provided a triangularly shaped hole 28 preferably passing entirely through the plate, each of these holes for a purpose that will presently appear.

In order that each can 25 may be positively retained in its correct position on the turntable, and with particular reference to Figs. 2, 3 and 4, it will be observed that the upwardly extending flanges of the angle members 18 constitute stops for the lower end portion of each can, and that there is provided an adjustable bracket member 30 to engage each can on the side farthest away from the post 7. Within each outer angle iron member 19, and substantially centrally disposed thereof, there is provided a filler block 31 to engage the face of the inwardly extending end 32 of a bracket 30, said end 32 being centrally slotted as at 33 to receive a bolt 34 by which the bracket is secured to the angle 19. It thus is made possible to accommodate ash cans of different sizes within certain limits, merely by positioning the bracket 30 so that each can is held on the

turntable at three points of circumferential contact.

The upper spindle 9 of the post 7 extends above the top plate 16 and engages a central socket of a hexagonally formed cap plate 40 which has cast on its upper face an upstanding ridge 41, see Figs. 5, 8 and 9, parallelly disposed to the perimeter of the plate 40 to provide a seat and an abutment for the inner ends of each cover section of the pit. In other words, there are provided in this particular construction six cover sections comprising plates each generally indicated by the numeral 42 and of triangular shape except that the outer edge is circular as indicated at 43 to fit the perimeter of the pit 2, and the opposite apex is cut off to provide a straight edge portion 44 to rest in the aforementioned seat and against the abutment comprising the outer side of the hexagonal ridge 41. The other sides of each cover section are made to conform with radii of the circular pit and are further provided with off-sets as indicated in Fig. 6 at 48 so that the edge of one cover section may support the edge of the adjacent section and the upper surfaces of all of said sections will lie in the same plane. To render this possible the aforementioned seats for the cover sections are formed with a recess 49 of a size to accommodate the offsets 48 of the sides of the cover sections, all as will be readily understood from the drawings.

Two of the cover sections, preferably diametrically opposed, are apertured as indicated at 45, one of said sections being so disposed that its aperture is in registry with the ash pit of a furnace, indicated in the drawings by the dotted line 46, so that the ashes from the grate may be directed to and fall through said aperture into one of the cans 25. The aperture of the other cover section has a lid 47 which, when removed, permits the sweepings of the furnace room floor to be directed into one of the ash cans, said lid 47 being sunk or recessed within the cover section to provide a flush floor surface, see Figs. 1 and 5. A similar lid may be provided for the aperture in the furnace ash pit if found necessary because of faulty draft.

A hexagonal lid 50 fits within the hexagonal ridge 41, and from Fig. 1 it will be readily seen that when the turntable is not to be rotated the entire exposed surface of the cover sections is in the plane of the furnace room floor, and further it will be seen that any weight placed on the cover sections will be borne thereby without affecting any of the rotatable parts. In other words the post 7 is adapted by this invention to always remain stationary, the ash cans and their turntable being adapted for rotation about said post.

The means for rotating the turntable comprises a bar 51 having an upstanding handle 52 at one end and a depending portion 53 at

the opposite end, the extreme end of the portion 53 being triangularly shaped in cross section to provide a key 54 which will fit each of the triangular openings 28 in the top plate 16 of the turntable. There is also provided a circular collar 55 immediately adjacent said key the periphery of said collar extending slightly beyond the apices of the key and serving as a stop as will be readily understood.

The hexagonal plate 40 supporting the cover sections is provided with an arcuate slot 56 the ends of which are enlarged as indicated at 57 to a diameter sufficient to permit the collar 55 of the operating handle to pass therethrough, but the width of the slot 56 is less than the diameter of said collar so that it is possible to pass the collar 55 through the slot only at an enlarged end thereof. The slot 56 is located in the plate 40 immediately over and in line with the path of travel of the triangular openings 28 of the top plate 16 of the turntable, and further located to control the positions of the cans 25. In other words, when a can 25 is correctly positioned below the ash hole 45, in the cover section under the furnace, a triangular hole 28 will be in registry with each enlarged end 57 of said slot. When said can has been filled with ashes the lid 50 is removed to uncover the slot 56 and the key end of the operating handle passed through one of the enlarged ends of said slot to engage the opening 28 therebelow. Upon movement of the handle from this position to a position occupying the other limit of said slot, see Fig. 8, the top plate 16 will have been rotated a distance equal to bring the next adjacent can 25 into correct position under the ash opening 45. By making the slot 56 as above described it is impossible to insert or remove the handle 51 without having a can in correct position.

When a can, filled with ashes, is to be removed from the turntable, one of the cover sections, preferably 60 and containing the lid 47, is lifted, no bolts being provided to secure this section to the adjacent sections. The opening thus made in the furnace room floor is ample to permit the removal of a can, and if the can positioned therebeneath is not the one desired, the turntable may be rotated until such can appear. The handle 51 should be left in operative position during the transfer of cans to and from the turntable to insure the proper setting of the turntable, when the cover section 60 is replaced, thus leaving a can under the ash pit opening 45. From Fig. 1 it will be seen that the cover sections are disposed in close proximity to the tops of the cans which permits observations to be made through both apertures 45 in the cover sections to ascertain the quantity of ashes in all the cans. Further it will be seen that the entire weight

of the turntable and cans is suspended from the top plate 16 which in turn is carried by the non-rotating vertical post 7 and, through the thrust bearing 15, permitted free rotational movement around said post regardless of any weight placed on the cover sections 42 and cap plate 40 which are also supported by said post.

It is obvious that those skilled in the art may vary the details of construction as well as arrangements of parts without departing from the spirit of the invention, and it is therefore not desired to be limited to the foregoing disclosure except as may be demanded by the claims.

What is claimed is:—

1. A rotary ash receiver comprising a turntable supporting a plurality of cans; a stationary post for supporting said turntable; a cover for said turntable directly supported by said post; and means to rotate said turntable to change the positions of said cans.

2. A rotary ash receiver comprising a turntable supporting a plurality of cans said turntable provided with means for securing each can in predetermined position; a stationary post for supporting said turntable; a cover for said turntable supported by said post; and means limited by said cover to rotate said turntable to change the position of said cans.

3. A rotary ash receiver comprising a turntable supporting a plurality of cans said turntable provided with adjustable means for securing each can in predetermined position; a cover for said turntable; a post for directly supporting said turntable and said cover; and means to rotate said turntable said means including means to insure predetermined positions of said cans.

4. A rotary ash receiver comprising a turntable supporting a plurality of cans said turntable comprising a floor and a casing extending upwardly therefrom; a stationary post passing through said casing for supporting said turntable; a cover for said turntable directly supported by said post; and means to rotate said turntable said means including means to positively establish predetermined positions of said cans.

5. A rotary ash receiver comprising a turntable supporting a plurality of cans said turntable comprising a bottom casting, a top casting, a casing rigidly secured to both of said castings, a floor secured to the bottom casting, angularly disposed stays between said top casting and said floor, and bearings associated with said castings; a stationary post for supporting said turntable said post passing through said casing and said castings and engaging said bearings; a cover for said turntable supported by said post; and means to rotate said turntable to change the positions of said cans.

6. A rotary ash receiver comprising a turn-table supporting a plurality of cans said turn-table comprising a bottom casting, a top casting, a casing rigidly secured to both of said castings, a floor secured to the bottom casting, angularly disposed stays between said top casting and said floor, and bearings associated with said castings; a stationary post for supporting said turntable said post disposed within said casing and provided with reduced end portions engaging said bearings and passing out of said casing through said castings, the lower end portion of said post fixedly retained with respect to the ground; 10 a cover for said turntable supported by the upper end portion of said post; and means to rotate said turntable to change the positions of said cans.

7. A rotary ash receiver comprising a turn-table supporting a plurality of cans said turn-table provided with radial members adapted to engage a can at two circumferential points and a bracket member between said radial members adapted to engage said can at a third circumferential point, all of said points being substantially equidistant; 25 a stationary post for supporting said turn-table; a cover for said turntable supported by said post; and means to rotate said turntable to change the positions of said cans.

8. A rotary ash receiver comprising a turn-table supporting a plurality of cans said turn-table provided with fixed radial members adapted to engage a can at two circumferential points and a movable bracket member between said radial members adapted to engage said can at a third circumferential point, all of said points being substantially equidistant; 40 a stationary post for supporting said turn-table; a cover for said turntable supported by said post; and means to rotate said turn-table to change the positions of said cans.

9. A rotary ash receiver comprising a turn-table supporting a plurality of cans; a stationary post for supporting said turntable; a cover for said turntable comprising a plurality of radial cover sections and a cap plate, said plate supporting the inner ends of said sections, and said plate directly supported by said post, and means to rotate said turn-table to change the positions of said cans.

10. A rotary ash receiver comprising a turn-table supporting a plurality of cans; a stationary post for supporting said turntable; a cover for said turntable including a cap plate supported by said post; and means passing through said plate to rotate said turn-table to change the positions of said cans.

11. A rotary ash receiver comprising a turn-table supporting a plurality of cans; a stationary post for supporting said turntable; a cover for said turntable including a slotted cap plate supported by said post; and means interlockingly engaging the slot of

said plate to rotate said turntable to change the positions of said cans.

12. A rotary ash receiver including a turn-table provided with cans to receive ashes disposed below the surface of the furnace room floor; a cover for said receiver constituting a portion of said floor; said cover free of contact with said turn-table; a vertical support for said turntable and said cover; and means to move said turntable.

13. A rotary ash receiver including a turn-table for cans; a cover for said turntable; stationary means directly supporting said turntable and said cover; and means to rotate said turntable.

14. A rotary ash receiver including a turn-table for cans including a lubricant holding chamber; a cover for said turntable; a stationary common support for said turntable and cover, said support passing through said chamber; and means to rotate said turntable.

15. In a device for receiving ashes the combination with a furnace of a rotary member for receiving the ashes, a cover for said member and spaced therefrom, and means directly supporting said member and said cover.

16. A rotary ash receiver and a cover therefor, the receiver having a central support comprising a fixed stationary member passing through said receiver and independently carrying the weights of the receiver and the cover.

17. A rotary ash receiver and a cover therefor, the receiver having a central support comprising a fixed stationary member passing through said receiver and independently carrying the weights of the receiver and the cover, and the cover including a member having means to positively limit the positions of the receiver.

18. A rotary ash receiver and a cover therefor, the receiver having a central support comprising a fixed stationary member passing through said receiver and independently carrying the weights of the receiver and the cover, and the cover including a member having means comprising a dumb-bell slot adapted to be engaged by a crank to positively limit the positions of the receiver.

19. A rotary ash receiver comprising a turn table supporting a plurality of cans; a post passing through said turn table; a cover for said turn table directly supported by said post; and means to rotate said turn table to change the positions of said cans.

20. A rotary ash receiver including a turn-table provided with cans to receive ashes disposed below the surface of the furnace room floor; a cover for said receiver constituting a portion of said floor, said cover free of contact with said turn-table; a vertical support for said cover passing through said turn-table; and means to move said turn-table.

21. A rotary ash receiver including a turn

table for cans; a cover for said turn table; stationary means directly supporting said cover, said means constituting the axis of said turn table; and means to rotate said turn table.

5 In testimony whereof I affix my signature.

JOSEPH A. WADDELL.
